SPEED WARNING SYSTEM

James C. Weaver, Harrisburg, Pa., assignor, by
mesne assignments, to Samuel Snyder, Harris-
burg, Pa.

Application January 23, 1939, Serial No. 252,452

1 Claim. (Cl. 200—80)

My invention relates to automotive vehicles, and has among its objects and advantages the provision of an improved excessive speed indicator.

In the accompanying drawings:

Figure 1 is an elevational view of my invention in association with the signal circuit which is diagrammatically illustrated;

Figure 2 is an elevational view partly in section of the governor controlled switch means;

Figure 3 is a view similar to Figure 2 illustrating the governor in another position;

Figure 4 is an end view of the governor mechanism in association with one section of its housing;

Figure 5 is a view taken substantially along the line 5—5 of Figure 3;

Figure 6 is a fragmentary detail view similar to Figure 5; and

Figure 7 is a fragmentary detail view illustrating one of the switch arms in cross section.

In the embodiment selected to illustrate my invention, I make use of a speedometer 10 which may be of the type employed in automotive vehicles. Speedometer 10 is provided with the usual flexible drive cable 12, in which cable I interpose a speed responsive unit 14 for closing the circuits through signal lamps when the vehicle exceeds a predetermined high speed. Referring to Figures 2 and 3, unit 14 includes a governor shaft 16 having square ends 18 for connection with the ends of the drive member 20, as at 22 in Figure 3. Upon the shaft 16 I mount a collar 24 having groups of spaced arms 25 between the arms of each group of which I mount a lever 28 for pivotal movement about the shaft 30. Each lever 28 carries a weight 32 at one end, while its opposite end is bifurcated at 34 for the reception of one end of a link 36 pivotally connected thereto at 38. The opposite end of each link is pivotally connected at 40 with a collar 42 keyed to the shaft 16 for rotation therewith but movable longitudinally thereon.

Collar 24 is fixedly related to the governor shaft 16, while a key 44 restrains the collar 42 from relative rotary movement on the shaft. Between the collars 24 and 42 I interpose a compression spring 46, one end of which lies in a short bore 48 in the collar 24 while its opposite end lies in a bore 50 in the collar 42. Collar 42 is slotted at 52 for accommodating one end of each of the links 36.

The governor mechanism is enclosed in a housing 54 comprising sections 56 and 58 flanged at 60 and connected into a unitary structure

through the medium of bolts 62. Section 58 is provided with a bearing 64 for rotatably supporting one end of the governor shaft 16. One end of the key 44 terminates flush with the end of the bearing 64, while the opposite end of the key terminates adjacent the offset wall 66 of the partition 68 formed integrally with the neck 70 extending laterally of the section 56. Thus the governor shaft 16 is restrained from relative longitudinal movement with respect to the bearing 64 and the bearing 72 which supports the other end of the shaft. Bearing 72 is carried by a plate 74 anchored to the neck 70 through the medium of screws 76. Figure 3 illustrates the adjustment of the governor under little or no speed, while Figure 2 illustrates the governor at a maximum speed.

Collar 42 includes a peripheral recess 78, and between the peripheral wall 80 and the inner face 20 of the neck 70 I mount a collar 82 which includes a flange 84 lying in the recess 78. Collar 82 slides freely relatively to the neck 70 and carries a flange 86 which extends inwardly of one face of the collar 42 so as to cross with the flange 84 to hold the collar 82 in connected relation with the collar 42. However, collar 42 may rotate freely relatively to the collar 82. Flange 86 is secured to the collar 82 by screws 88.

Figure 3 illustrates the neck 70 as being provided with two threaded bosses 90 for the reception of connecting elements 92 which secure the flexible cables 94 to the bosses. Each flexible cable encloses an electric wire 96 connected with a terminal screw 98 carried by an insulating sleeve 100. Each terminal screw 98 includes a contact head 102. In Figure 1, I illustrate one of the wires 96 as being connected with a manually actuated switch 104 arranged to be moved into conducting relation with the terminal 106 connected with a wire 108 leading to the ammeter 110. The latter is connected with a wire 112 leading to a source of current 114 grounded at 116. The other wire 96 is connected with a wire 118 leading to a lamp 120 grounded at 122. Lamp 120 is located in any advantageous position at the rear of the vehicle for excessive speed indicating purposes. Wire 118 also leads to a signal lamp 124 grounded at 126, which lamp is located in any suitable position on the forward part of the vehicle for excessive speed indicating purposes. A wire 128 connects the wire 118 with a pilot lamp 130 which serves an indicating function for the driver of the vehicle. Lamp 130 is grounded at 132. Lamps 120 and 124 should embody a contrasting color for excessive speed indicating pur-

poses, such as blue or other color which distinguishes from the usual red lamps employed in connection with stop and tail lights.

The circuits through the lamps 120, 124 and 130 are closed through the medium of the governor mechanism, which governor mechanism is responsive to variations in speed of the vehicle. Collar 82 is provided with a semi-circular slot 134 within which I secure a similarly shaped conducting strap 136 having right angular arms 138 provided with contacts 140 arranged to be moved into conducting relation with the contact heads 102. Arms 138 extend through slots 142 in the partition 68, which slots are of sufficient depth to accommodate slight flexure of the arms as the contacts 140 are brought into axial relation with the heads 102. Contact between the heads 102 and the contacts 140 close the circuits through the lamps. Figure 3 illustrates the arms 138 as being slotted at 144 to receive the pins 146 carried by the contacts, which pins are threaded for the reception of nuts 148 which permits the contacts 140 to be fixedly related to their respective arms 138 in different positions for changing the speed responsiveness of the governor mechanism with respect to opening and closing the electric circuits at different vehicle speeds.

Coupling members 92 are in the nature of nuts, each provided with a lug 150 bored for the reception of a seal wire 152 passing through an opening in a lug 154 formed on the neck 70. The ends of the wire 152 are provided with the usual sealing element 156. Thus the coupling members 92 are made secure against tampering in that the coupling members cannot be removed for the purpose of unloosening the wires 96. Similarly, the plate 74 is provided with lugs 158 and the neck 70 is provided with lugs 160 which co-

operate with the lugs 158 for the reception of seal wires 170 provided with seal elements 172. Thus plate 72 cannot be removed so as to protect the contacts 140 from adjustment through unauthorized tampering.

Without further elaboration, the foregoing will so fully illustrate my invention that others may, by applying current knowledge, readily adapt the same for use under various conditions of service.

I claim:

In a speed indicating signal of the type described, a governor comprising a housing having a drive shaft rotatably journaled therein, a transverse partition in said housing and having openings, contacts carried by said housing for connection with wires of a signal circuit, a first collar keyed on said shaft for rotation therewith but movable longitudinally thereon, speed responsive means keyed to said shaft and having operating connections with said first collar for moving the latter longitudinally of said shaft upon rotation of the latter, a second collar slidable inside said housing longitudinally of said shaft, said first collar being rotatable relatively to said second collar with the latter connected with the first collar to be moved therewith in its movement longitudinally of said shaft, a pair of switch arms fixedly connected with said second collar and electrically connected, said switch arms extending through the openings in said partition, and second contacts carried by said switch arms and normally spaced from said first-mentioned contacts, said second contacts being arranged to be moved into circuit closing engagement with said first-mentioned contacts when said switch arms and said second collar are moved a predetermined distance by said first-mentioned collar.

JAMES C. WEAVER.
